UNITED STATES PATENT OFFICE.

OTTO DANNEHL, OF BERLIN-ZEHLENDORF, GERMANY, ASSIGNOR TO NAAMLOOZE VENNOOTSCHAP MACHINERIEEN EN APPARATEN FABRIEKEN, OF UTRECHT, NETHERLANDS.

PRESSURE FRAME FOR SLIDING WINDOWS.

Application filed October 28, 1924, Serial No. 746,424, and in Germany December 1, 1923.

This invention relates to improvements in pressure frames for sliding windows of that type, in which the pressure frame is pressed in fixed positive manner against the window frame at the upper end, and in loose positive and resilient manner at the lower end, and wherein, by the operation of a single handle, the said pressure frame may be pressed against or withdrawn from the window in such manner that the window may be freely moved up and down.

Whilst in the case of such pressure frames provision has already been made for the supporting member for the window to be withdrawn automatically from the weather rail upon the lifting of the pressure frame, according to the invention the pressure frame is provided with a device, which automatically releases the topmost position of said frame upon the closing of the window, so that the pressure frame, due to its own weight and as a result of inclined guideways, slides against the window frame and thereby presses the supporting member on to the weather rail. In order to facilitate the lateral drop of the pressure frame under its own weight, and to render the pressure against the window frame more effective, the invention also provides for a spring mounted on the upper locking member above the window aperture, said spring strongly tending to force the pressure frame downwards.

The invention is illustrated by way of example in the accompanying drawing, in which—

Fig. 1 is a front elevation of the improved window.

Fig. 2 is a vertical section on the line A—A in Fig. 1.

Fig. 3 is a detail section of the device for pressing the pressure frame against the window frame upon downward movement.

Fig. 4 is a section corresponding to Fig. 3, but showing the pressure frame raised.

Figs. 5-7 are detail sections showing the various positions of the pressure frame during the operation of the handle.

Fig. 8 shows in section the position of the guide members and cooperating parts in the topmost position of the window.

The pressure frame 1 lies against the whole periphery of the frame 2 of the window 3. The window is capable of being raised and lowered by means of the hand

grip 4 mounted on the upper part of the window frame. The pressure frame 1 possesses at the top two inclinedly arranged guide members 5 (Figs. 1, 2, 3 and 4), which are furnished with lugs 6 as slideway for a leaf spring 7. These guide members 5 move in slots 8 (Figs. 2, 3 and 4) in an angle bar 9, which is secured above the window aperture upon the upper locking member 10. This arrangement causes the pressure frame, upon a downward movement 65 granted thereto under the effect of its own weight and with the assistance of the leaf spring 7, to be firmly pressed against the window frame, and upon an upward movement effected by hand to move away from 70 the window frame and release the same. This pressure against the window frame occurs at any desired elevated position of the window, i. e., also upon only part opening or closing. If on account of swelling of the 75 wood the distance between the pressure and window frames has decreased, the pressure frame will move to a slight extent downwardly to the point of contact. If, however, the distance has been increased on account 80 of a shrinkage of the wood, this will be automatically adjusted by the pressure frame sinking to a correspondingly greater extent until same presses against the window frame, by which the downward movement thereof 85 is limited. A tight closure in the direction towards the window frame is obtained in all cases, however, by the upper fixed positive guiding of the pressure frame.

This adaptation of the vertical movement 90 of the pressure frame to the particular position of the window frame is rendered possible in the case of this form of embodiment by the pressure frame being resiliently pressed against the window frame at the bottom, namely, also under the effect of its own weight and with the assistance of the leaf spring 7. The release of this lower mechanism is effected by means of the catch or grip 11 on the lower part of the pressure frame (Figs. 1, 2 and 5-7). The catch 11 is formed as an elbow piece, and is pivotal around an axle 12, which is mounted in two hinge-blocks 13, of which, in the vertical sections in Figs. 2 and 5-7, only the rear one 100 is to be seen. The elbow piece 11, by means of its short, fork-like end 14, hingedly encompasses a sliding block 16 by means of 105

set screws 15, which block is horizontally bored, and capable on the rod 17 of moving against a spring 18, tending to force same towards the left, between the two members bearing the rod 17 of the double bent member 19, secured to the pressure frame. The movement of the elbow piece 11 around the pivot 12 allows the sliding block, and therefore the pressure frame, to perform a circular movement, the vertical components of which represent a vertical movement of the pressure frame, and the horizontal components a horizontal movement. The movement is then limited when the two pivot points 12 and 15 are located in the same vertical (Fig. 5). A certain impulse is required in this case for the elbow piece 11, in order to allow the force directed vertically downwards by the pressure frame to exert a horizontal pressure upon the window frame.

This impulse may be automatically granted by means of the window moved upwardly by the hand catch 4. For this purpose a hook-shaped abutment 20 is provided on the lower part of the window frame 2 (Figs. 2 and 5-7), which abutment in the last part of the upward movement, shortly before the complete closing of the window, and before the projection 21 (Figs. 2 and 5-8) thrusts upon the weather board 22, moves the elbow piece 11, by means of the elbow piece 24 rotatable around the axle 23, out of its stable position, so that upon the further upward movement of the window, under the pressure of the spring 18, the nose 21 is able to rest upon the weather board 22, as illustrated in Figs. 6 and 7.

The withdrawal of the projection 21 from the member 22 before the lowering of the window can, for avoiding a strap, and in continuation of the idea of only requiring one hand for the manipulation of the window, also be effected automatically. For this purpose, in the form of embodiment shown, two cranked metal plates 25 (Figs. 1 and 8) each having a slot 26 are mounted upon the lower part of the window frame, through which slots the angle pieces 27 on the pressure frame 1 protrude downwardly. When, prior to the opening of the window, the pressure frame 1 is lifted from the window frame 2, the angle pieces 27 carry the window frame to such extent with them that the projection 21 leaves the member 22. In the drawing the window frame is composed of one piece of suitably bent sheet metal, and the projection is bent out from same.

The opening of the window is effected by depressing the catch 11. The pressure frame

is both lifted out of the position shown in Figs. 2 and 7, as well as withdrawn from the window frame, as shown in Figs. 5 and 6, namely, upon its whole periphery. The window is thus free, and able to slide down in the guide grooves, for, as shown in Fig. 8, upon the horizontal movement of the pressure frame illustrated in Figs. 5 and 6 the window frame is likewise taken in this direction. The pressure frame and pressure frame bar are shown in the drawing to be 70 of wood; they may, however, also be made of other material.

What I claim is

1. In combination, a window frame, a vertically slidable window mounted in said frame, a pressure frame associated with the window, means at the upper extremity of the pressure frame for guiding the latter into engagement with the window incident to downward movement of the pressure frame, means for loosely guiding the lower portion of the pressure frame, a pivoted lever associated with the last mentioned guiding means and operable during movement in one direction to elevate and withdraw the lower portion of the pressure frame from the window and, during movement in the opposite direction to lower the pressure frame, and means coacting with said lever to resiliently press the lower portion of the pressure frame against the window the pressure frame is in its lowered position.

2. An arrangement as claimed in claim 1 characterized by the provision of means normally tending to move the pressure frame downwardly, the first mentioned guiding means, acting, in conjunction with the last mentioned means to move the pressure frame into engagement with the window.

3. An arrangement as claimed in claim 1 characterized by the provision of spring means normally tending to press the pressure frame downwardly, the first mentioned guide means including inclined members, and means coacting therewith tending to thrust the pressure frame laterally toward the window incident to downward movement of the pressure frame.

4. An arrangement as claimed in claim 1 characterized by the provision of means actuated by the window incident to the upward movement of the latter to displace said lever and cause the partial elevation of the pressure frame whereby the latter is moved out of window engaging position.

In testimony whereof I have affixed my signature.

OTTO DANNEHL.
